Primary Examiner—Ralf T. Seifert*Attorney, Agent, or Firm*—Hill, Steadman & Simpson[57] **CLAIM**

The ornamental design for pull tab for slide fastener sliders, as shown.

DESCRIPTION

FIG. 1 is a front view of a pull tab for slide fastener sliders;

FIG. 2 is a right side view of the pull tab for slide fastener sliders of FIG. 1;

FIG. 3 is a plan view of the pull tab for slide fastener sliders of FIG. 1;

FIG. 4 is a base view of the pull tab for slide fastener sliders of FIG. 1;

FIG. 5 is a cross-sectional view taken on line A—A of FIG. 1; and,

FIG. 6 is a cross sectional view taken along the line 6—6 of FIG. 1.

The broken line showing of a slider body is for illustrative purposes only and forms no part of the claimed design.

FIG. 1

FIG. 2

FIG. 3

FIG. 4

FIG. 5

FIG. 6
